BOOKBINDING MACHINERY

Robert Leighton, London, England

Application October 26, 1938, Serial No. 237,121
In Great Britain November 4, 1937

12 Claims. (Cl. 11—1)

This invention relates to an apparatus, which is intended for use in the forwarding stage of bookbinding, in order to reduce the sewing swell or thickness of the stitched and preferably glued edge of a book substantially to the normal thickness of the book prior to application of a case or cover thereto. This step or operation is known as "nipping" and is usually performed by placing the stitched edge of a book in a press having a reciprocating head or plunger.

According to this invention books to be treated are carried between endless bands or belts of canvas or other suitable material through a plurality of sets or pairs of pressure rollers which are of such number and are so disposed that pressure is exerted upon the books without intermission for a sufficient period of time to reduce to some degree of permanence the thickness of the sewing swells or stitched edges. The belts are of sufficient thickness and are of suitable material that they present a substantial inflexibility when passing between the pressure rollers. The adjacent pairs of pressure rollers are also arranged sufficiently close to one another that the pressure exerted by said rollers through the belts to the books is not allowed to be relaxed throughout the passage of the books through the sets of pressure rollers. Moreover flat guide plates or members are mounted between adjacent rollers to assist in maintaining the pressure on the books during their passage through the apparatus and to prevent distortion of the books as they pass from one set of pressure rollers to another set. The distance between the members of each pair of rollers can be adjusted as desired and preferably the distance between the members of each pair is separately determined. Only the intermediate parts of the adjacent reaches of the two belts are acted upon by the pressure rollers, the parts of the reaches on both sides of the series of pressure rollers serving to grip the books and retain them in position during feeding to and movement away from the pressure rollers, such gripping of the books serving as a substitute for manual feeding of the books between the pressure rollers and removal thereof as the books pass beyond the pressure rollers. The preliminary gripping of the books between the belts prior to the pressing operation ensures that the outer pages of the books do not become creased, distorted or otherwise damaged during pressure thereon. Furthermore one of the belts may extend beyond the other belt at both ends of the apparatus, and serves thereby as a conveyor band

or belt to feed the books to and discharge them from the apparatus.

The invention is illustrated by way of example in the accompanying drawings in which

Figure 1 is a side view of a machine according to this invention,

Figure 2 is a partial plan thereof with several of the roller adjusting members and the endless bands omitted, and

Figure 3 is a partial longitudinal section on the line III—III, Figure 2, with some of the rollers omitted.

As shown in the drawings, two endless bands or belts 1, 2, of canvas or other suitable material are arranged one above the other and pass around rollers 3, 4 and 5, 6 respectively, the axes of the said rollers being horizontal and parallel to one another. The position of the rollers 3, 4, 5 and 6 are suitably adjustable in order that the tension of the belts or bands 1 and 2 may be varied as desired. The bands or belts are of sufficient width to receive one or more books, whilst the lower band or belt 2 extends beyond the upper band or belt 1 and serves as a conveyor band for feeding books to the apparatus and for discharging them therefrom.

Intermediate of its length a series of driven rollers 7, for example, five rollers as shown, carried in bearings formed in bearing blocks 8 engage the underside of the upper reach of the lower band or belt 2. The upper side of the lower reach of the top band or belt is similarly engaged by a series of driven rollers 9 that are carried in bearings formed in bearing blocks 10 and are arranged opposite the driven rollers 7 which engage the lower band or belt. Thus the belts 1, 2, pass between sets or pairs of rollers that serve as pressure rollers, the roller in each series being arranged sufficiently close together to assist in maintaining those parts of the bands or belts extending between them sufficiently inflexible to transmit pressure from the rollers continually to a book throughout its passage through the sets of rollers. The journals or bearings of the upper rollers 9 are carried in vertical guides 11 and the said upper rollers are each independently adjustable to vary the distance from its co-acting lower roller 7. The adjusting means for each roller 9 consists of a spindle 12 arranged transversely of the machine above its associated roller and carried in bearing blocks 13 supported upon the guides 11, the bearing blocks 13 being retained in position by bolts 14 and springs 15 that are mounted about the bolts 14 and press upon the bearing blocks with a pressure that

can be regulated by nuts 16. The spindle 12 has keyed thereon two bevel wheels 17 that engage with bevel wheels 18 secured upon vertical screw threaded rods 19 which engage screw threaded holes in the bearing blocks 10 or in plates secured thereto. Thus upon rotation of a spindle 12, which is facilitated by a squared end portion thereof, its associated rods 19 are caused to rotate through the gearing 17, 18, such 5 rotation of the rods 19 causing the bearing blocks 11 to move towards or away from the bearing blocks 8, thereby altering the distance between the rollers 7 and 9. In order that successive bearing blocks 10 are limited in the closeness of their approach towards their associated bearing block 8, the said movable bearing blocks 10 are provided with extensions or lugs 20 that rest upon shoulders 21 on adjacent blocks. Thus, as can be seen from Figure 3, each pair of rollers 10 can be set closer together than the previous pair 15 of rollers by an amount that is limited by the extensions 20 and the co-operating shoulders 21 of adjacent bearing blocks, whereby if desired, the pressure on a book passing through the machine can be gradually increased to a limited amount.

Furthermore the upper driven rollers 9 are preferably so disposed as shown relatively to the end rollers 3, 4, about which the upper band or belt 1 passes, that those parts of the lower each of the said band or belt between the end rollers 3 and 4 and the upper driven rollers 9 are inclined towards the upper reach of the lower band or belt in order that when a book carried by the lower band or belt engages the lower reach of the upper band or belt, the pressure exerted upon the book gradually increases until it passes between the sets of driven rollers where the pressure is at a maximum. By this arrangement the book is subjected to a suitable pressure for a sufficient period of time to cause the sewing swell or stitched edge of a book to be reduced with some degree of permanence to the normal thickness of the book. After passing through the sets 30 of driven rollers the pressure on the book is gradually decreased until it passes clear of the upper band or belt. The holding of the books between the belts prior to and subsequent to the passage between the driven pressure rollers replaces manual gripping for feeding a book to pressure exerting means and for removing it therefrom after subjection to the necessary pressure.

It has been found desirable to drive positively 55 each of the rollers 7 and 9. To this end each of the first four lower rollers 7 has keyed to its spindle a toothed wheel 22, the adjacent toothed wheels 22 being connected by idle or freely rotatable pinions 23. The spindle of the central lower 60 roller is extended and has keyed thereon a toothed wheel 24 and a gear wheel 25 which is suitably driven. The toothed wheel 24 is connected through a freely rotatable toothed wheel 26 to a toothed wheel 27 keyed on the spindle of 65 the fifth lower roller. The upper rollers are connected by suitable gearing to their associated lower rollers, such connection being effected in the case of the first, third and fifth pair of rollers by securing gear wheels 28 to the spindles of 70 such lower rollers, at the ends thereof remote from the toothed wheels 22, and securing to the spindles of the upper rollers, gear wheels 29. The gear wheels 28 and 29 are connected by suitable gear wheels 30 carried by an articulated frame comprising two pairs of arms 31, 32, piv-

totally mounted on the spindles of the rollers and hingedly connected together at the spindle of one of the gear wheels 30. The second and fourth pair of rollers are similarly connected by gearing but in these cases the gear wheels 29 are 5 mounted above the gear wheels 22 and are connected thereto by gear wheels 30 carried, as shown, by articulated frames 31, 32. With this arrangement all of the rollers 7 and 9 are positively driven and the gearing can thus continue 10 in operation during any requisite adjustment of the positions of the rollers.

The rollers 4 and 6 are also positively driven. This is effected by connecting lay shafts 38 and 39 to the fifth upper roller and lower roller respectively through toothed and chain gearing. The lay shaft 38 is connected to the roller 4 through chain gearing whilst the lay shaft 39 is similarly connected to the roller 6. Idle rollers 40 and 41, preferably faced with hard india rubber or the like, are carried by a pivotally mounted frame and press the endless belt or band 1 against the roller 4. Owing to the rollers 40 and 41 being carried by a pivotally mounted frame, such rollers press against the belt or band 25 with an equal pressure which can be varied by adjusting the position of the frame. An idle roller 42 also presses the endless belt or band 2 against the roller 6. Such idle rollers 40, 41 and 42 serve to prevent slipping of the endless belt 30 or bands and enables an increased driving effort to be transmitted thereto by the rollers 4 and 6.

Separate guide plates 33 are arranged between adjacent driven rollers 7 and 9, which guide plates are adapted to engage the belts or bands 1 and 2 to prevent any tendency of the said belts or relax the pressure exerted on the books as they pass from one set of rollers to another set which would allow distortion to be imparted to the book as it engages each pair of pressure rollers. The guide plates between the lower rollers are preferably immovably mounted on the bearing blocks 8, but each of the guide plates between the upper rollers is secured to the bearing blocks 10 carrying the preceding roller 9 and 45 is movable therewith. An inclination of each guide plate towards its following roller is possible by permitting the bearing blocks that support the rollers 9 to turn slightly about the axes of the rollers, against the action of springs. Such 50 inclination of a plate is effected when the shoulder 21 of the bearing block on which it is supported is pressed downwardly by the co-operating extension 20 on an adjacent bearing block. If desired, however, the said guide plates may be 55 supported, at the side thereof remote from the feeding-in end of the apparatus, upon the bearing of an adjacent roller whilst its side or end nearest the feeding-in end of the apparatus is held in a requisite position by springs. Upon adjustment of the roller, the guide plate supported by the bearing thereof will assume a suitable 60 inclination.

Furthermore, in order to grip the books to be passed between the rollers to a greater extent 65 than is possible by the convergence of the upper and lower belts and to ensure that they will be retained in a requisite position as they are fed to the pressure rollers, a pair of gripping rollers 34 may be disposed in front of the first pair of 70 driven pressure rollers. The rollers 34, which do not extend the entire width of the belts or bands, are mounted in plates 35 which are respectively secured to bearing blocks 8 and 10 of the first pair of pressure rollers and are spaced 75

a short distance away from the belts or bands. Books are fed from a table 36 on to the upper reach of the endless travelling band 2, preferably two at a time, in which case the sewing swells of the two books are remote from one another. The books thus fed to the endless band 2 are conveyed towards the pressure rollers, but before they reach such rollers they are engaged by the lower reach of the upper endless travelling band 1. The books are thus gripped between the two endless bands and thereafter the pressure is increased upon that part of each book which passes between the rollers 34. Thereafter the books pass between the several series or pairs of pressure rollers and, after passing between all of the pressure rollers, they are carried by the endless band 2 towards a receiving table 37 and prior to reaching such table the upper endless band 1 is moved out of engagement therewith.

Should the books that are fed to the machine be of greater thickness than that to which the machine has been adjusted, the bearing blocks 10 and the bearing blocks 13 are raised against the action of the springs 15, thereby preventing damage to the machine. The rollers 3 and 4 are similarly resiliently mounted.

It can thus be seen that the machine enables a number of books to be successively subjected to pressure in a rapid manner.

30. I claim:

1. A machine for subjecting the sewing swell of books to pressure, comprising two series of rollers forming a plurality of pairs of pressure rollers, plates extending between adjacent rollers of each series, a travelling endless band having a reach which passes between the series of rollers and engages one series thereof and the plates extending therebetween, and a second travelling endless band having a reach which passes between the two series of rollers and engages the second series thereof and the plates therebetween.

2. A machine for subjecting the sewing swell of books to pressure, comprising a series of rollers, fixed bearings in which said rollers are mounted, a second series of rollers, adjustable bearings in which said second series of rollers are mounted, said series of rollers forming a plurality of pairs of pressure rollers, plates extending between adjacent rollers of each series, a travelling endless band having a reach which passes between the series of rollers and engages one series thereof and the plates extending therebetween, and a second travelling endless band having a reach which passes between the two series of rollers and engages the second series thereof and the plates therebetween.

3. A machine for subjecting the sewing swell of books to pressure, comprising a series of rollers, fixed bearings in which said rollers are mounted, a second series of rollers, adjustable bearings in which said second series of rollers are mounted, said series of rollers forming a plurality of pairs of pressure rollers, means for positively driving each roller, plates extending between adjacent rollers of each series, a travelling endless band having a reach which passes between the series of rollers and engages one series thereof and the plates extending therebetween, and a second travelling endless band having a reach which passes between the two series of rollers and engages the second series thereof and the plates therebetween.

4. A machine for subjecting the sewing swell of books to pressure, comprising a series of spindles,

rollers fixedly mounted on said spindles, plates extending between adjacent rollers, an endless travelling band the upper reach of which has its central portion passing over and engaging said rollers and plates and the end portions of which act as conveyors, a second series of spindles, rollers fixedly mounted on said spindles and arranged in register with and above the first series of rollers, plates extending between adjacent rollers of said second series, and a second endless travelling band having the central part of its lower reach passing under and in contact with said second series of rollers and plates and having its end portions inclined towards the upper reach of said second endless band.

5. A machine for subjecting the sewing swell of books to pressure, comprising a series of spindles, rollers fixedly mounted on said spindles, plates extending between adjacent rollers, an endless travelling band the upper reach of which has its central portion passing over and engaging said rollers and plates and the end portions of which act as conveyors, a second series of spindles, rollers fixedly mounted on said spindles and arranged in register with and above the first series of rollers, plates extending between adjacent rollers of said second series, a second endless travelling band having the central part of its lower reach passing under and in contact with said second series of rollers and plates and having its end portions inclined towards the upper reach of said second endless band, and means for adjusting independently the distance between each roller of one series and the roller of the second series in register therewith.

6. A machine for subjecting the sewing swell of books to pressure, comprising a series of spindles, rollers fixedly mounted on said spindles, plates extending between adjacent rollers, an endless travelling band the upper reach of which has its central portion passing over and engaging said rollers and plates and the end portions of which act as conveyors, a second series of spindles, rollers fixedly mounted on said spindles and arranged in register with and above the first series of rollers, plates extending between adjacent rollers of said second series, a second endless travelling band having the central part of its lower reach passing under and in contact with said second series of rollers and plates and having its end portions inclined towards the upper reach of said second endless band, means for adjusting independently the distance between each roller of one series and the roller of the second series in register therewith, gear wheels keyed on the spindle of each shaft, a train of gear wheels connecting the gear wheels on each roller spindle of one series with the gear wheels on the roller spindles of the registering rollers of the second series, and an articulated frame carrying the train of gear connecting each pair of rollers.

7. A machine for subjecting the sewing swell of books to pressure, comprising two series of spindles with their axes parallel to one another, driving means for rotating said spindles, rollers fixedly mounted on said spindles and forming a plurality of pairs of pressure rollers, plates extending between adjacent rollers of each series, fixed bearing blocks in which the spindles of one series are carried, movable bearing blocks in which the spindles of the second series are carried, means for adjusting independently each pair of movable bearing blocks carrying a spindle towards or away from the fixed bearing blocks, a travelling endless band having a reach which

passes between the series of rollers and engages one series thereof and the plates extending therebetween, and a second travelling endless band having a reach which passes between the two series of rollers and engages the second series thereof and the plates therebetween.

8. A machine for subjecting the sewing swell of books to pressure, comprising two series of spindles with their axes parallel to one another, driving means for rotating said spindles, rollers fixedly mounted on said spindles and forming a plurality of pairs of pressure rollers, plates extending between adjacent rollers of each series, fixed bearing blocks in which the spindles of one series are carried, resiliently mounted and movable bearing blocks in which the spindles of the second series are carried, means for adjusting independently each pair of movable bearing blocks carrying a spindle towards or away from the fixed bearing blocks, a travelling endless band having a reach which passes between the series of rollers and engages one series thereof and the plates extending therebetween, and a second travelling endless band having a reach which passes between the two series of rollers and engages the second series thereof and the plates therebetween.

9. A machine for subjecting the sewing swell of books to pressure, comprising two series of spindles with their axes parallel to one another, rollers fixedly mounted on said spindles and forming a plurality of pairs of pressure rollers, gearing for connecting the spindles of one series to rotate them in one direction, gear wheels keyed on each spindle, a train of gearing connecting each gear wheel on one series of spindles with a gear wheel on a spindle of the second series of spindles, an articulated frame for carrying each train of gearing, plates extending between adjacent rollers of each series, fixed bearing blocks in which the spindles of one series are carried, resiliently mounted and movable bearing blocks in which the spindles of the second series are carried, means for adjusting independently each pair of movable bearing blocks carrying a spindle towards or away from the fixed bearing blocks, a travelling endless band having a reach which passes between the series of rollers and engages one series thereof and the plates extending therebetween, and a second travelling endless band having a reach which passes between the two series of rollers and engages the second series thereof and the plates therebetween.

10. A machine for subjecting the sewing swell of books to pressure, comprising two series of spindles with their axes parallel to one another, rollers fixedly mounted on said spindles and forming a plurality of pairs of pressure rollers, gearing for connecting the spindles of one series to rotate them in one direction, gear wheels keyed on each spindle, a train of gearing connecting each gear wheel on one series of spindles with a gear wheel on a spindle of the second series of spindles, an articulated frame for carrying each train of gearing, plates extending between adjacent rollers of each series, fixed bearing blocks in which the spindles of one series are carried, resiliently mounted and movable bearing blocks in which the spindles of the second series are carried, means for adjusting independently each pair of movable bearing blocks carrying a spindle towards or away from the fixed bearing blocks, a shoulder on each movable bearing block, a lug on each of said movable bearing blocks to engage

the shoulder on an adjacent movable bearing block, a travelling endless band having a reach which passes between the series of rollers and engages one series thereof and the plates extending therebetween, and a second travelling endless band having a reach which passes between the two series of rollers and engages the second series thereof and the plates therebetween.

11. A machine for subjecting the sewing swell of books to pressure, comprising two series of spindles with their axes parallel to one another, rollers fixedly mounted on said spindles and forming a plurality of pairs of pressure rollers, gearing for connecting the spindles of one series to rotate them in one direction, gear wheels keyed on each spindle, a train of gearing connecting each gear wheel on one series of spindles with a gear wheel on a spindle of the second series of spindles, an articulated frame for carrying each train of gearing, plates extending between adjacent rollers of each series, fixed bearing blocks in which the spindles of one series are carried, resiliently mounted and movable bearing blocks in which the spindles of the second series are carried, means for adjusting independently each pair of movable bearing blocks carrying a spindle towards or away from the fixed bearing blocks, a shoulder on each movable bearing block, a lug on each of said movable bearing blocks to engage the shoulder on an adjacent movable bearing block, a travelling endless band having a reach whose central portion passes between the series of rollers and engages one series and the plates extending therebetween, and a second travelling endless band having a reach whose central part passes between the two series of rollers and engages the second series thereof and the plates therebetween and whose end portions are inclined away from the first endless band.

12. A machine for subjecting the sewing swell of books to pressure, comprising two series of spindles with their axes parallel to one another, rollers fixedly mounted on said spindles and forming a plurality of pairs of pressure rollers, gearing for connecting the spindles of one series to rotate them in one direction, gear wheels keyed on each spindle, a train of gearing connecting each gear wheel on one series of spindles with a gear wheel on a spindle of the second series of spindles, an articulated frame for carrying each train of gearing, plates extending between adjacent rollers of each series, fixed bearing blocks in which the spindles of one series are carried, resiliently mounted and movable bearing blocks in which the spindles of the second series are carried, means for adjusting independently each pair of movable bearing blocks carrying a spindle towards or away from the fixed bearing blocks, a shoulder on each movable bearing block, a lug on each of said movable bearing blocks to engage the shoulder on an adjacent movable bearing block, a travelling endless band having a reach whose central portion passes between the series of rollers and engages one series and the plates extending therebetween, a second travelling endless band having a reach whose central part passes between the two series of rollers and engages the second series thereof and the plates therebetween and whose end portions are inclined away from the first endless band, and gripping rollers which engage the endless bands in front of the pressure rollers.

ROBERT LEIGHTON.
